John Neill
Attorney

UNITED STATES PATENT OFFICE.

DAVID S. NEILL, OF GENOA, ITALY.

LIFEBOAT.

Application filed December 17, 1927, Serial No. 240,790, and in Italy November 19, 1927.

This invention relates to life-saving at sea and its object is to provide an appliance which will advantageously substitute the type of lifeboats at present generally adopted on board steamships, which in practice prove to be unsafe and unreliable even in exceptionally favourable circumstances.

It is an obvious fact that nautical life-saving appliances have not improved concurring with the enormous progress of marine constructions generally, consisting as they do in the universally adopted ordinary open life boat, apt to dangerously list when being launched with its complement of passengers, to be seriously damaged by smashing against the ship's side, and easily capsizable when afloat under the action of disordinate movements of panic stricken passengers unaccustomed to boat manœuvring particularly in a rough sea. Furthermore once the open boat has managed to get clear of the ship, if the weather is at all inclement, the occupants, a large percentage of whom may consist of women and children, are exposed for an indefinite period of time to the most severe suffering.

The appliance forming the object of the present invention is meant to obviate the dangers and generally lamented inconveniences which the passengers and crew are normally exposed to in the event of their having to abandon the ship on the high seas, reducing to a minimum the serious risks attending the lowering of ordinary lifeboats, avoiding the danger of capsizing in the roughest sea and affording an effective shelter and protection to the occupants in any sort of weather in any season and in any latitude.

The principle of the invention will be better understood when referring to the accompanying drawings and description thereof, illustrating a preferred embodiment of the invention.

In the drawings:

Figure 1 is a side elevation of an improved lifeboat, with the side being removed to show the internal construction;

Figure 2 is a plan view, one of the upper longitudinal quarters of the hull plating removed to show the interior arrangement;

Figure 3 is in enlarged scale a vertical section of the apparatus, towards the stern portion.

As it is clearly shown, the boat's body comprises a substantially cylindrical hull closed by hemispherical or otherwise rounded ends,

It will be generally advisable to construct this hull of a light and resistant metal, such as duralumin or special steel, the plating being supported by strong annular ribs 2, to which it is riveted. A double bottom 3 with raised floors is constructed along the whole length of the quickwork of the boat and in this double bottom fresh water and fuel tanks are arranged. Besides, this double bottom may also be completely ballasted with water for improving the stability of the boat. The stem portion of the submerged part of the hull can be conveniently shaped in order to diminish the resistance to movement, while the stern portion of the quickwork is suitably recessed at 4 for the arrangement of a rudder 5 and the screw propeller 6. The boat is ordinarily propelled by an internal combustion engine 8 suitably situated amidships to drive, by means of a suitable shaft 8', to said screw 6. A hand steering wheel 10 for the rudder is suitably situated amidships.

Above the helmsman's station on the hull 1, a cylindrical dome with water-tight hinged cover 12 is arranged, provided with suitable side and upper surveying port holes for the helmsman. Inside, along the sides and on the centre line, where it is possible, benches 14 for the occupants are arranged. The hull 1 is provided besides the water tight dome 11, also with a number of suitable lateral doors 15 arranged so as to be easily hermetically closed either from the interior or the exterior. A suitable rubber, hemp gasket or other type of horizontal fender 16 is fitted all around the hull, along the periphery of its maximum horizontal section, and other vertical fenders are applied on to the hemispherical stern and stem convexities, while on a plane below that of the horizontal fender and projecting out of the hull are a number of ball-like fender rollers 18 constituted generally of a rubber core lined with a thick cork layer and enclosed in weaved or twined hemp rotatably supported in suitable stirrup members bolted to the corresponding hull plating.

A suitable number of ventilating cowls 19 are arranged in suitable positions, in order to provide for the airing of the interior. Furthermore suitable means are provided for engaging and disengaging the boat suspending gear, automatically and by hand from the interior of the hull.

The dimensions of the boat will depend of course, upon the number of persons it is designed to carry (generally from 60 to 100

each boat) in relation to the deck space available on each particular type of vessel for installation of life-saving appliances, and it is obvious that the launching devices will have the resistance and power as required. The new type of boat besides the fresh water supply and the fuel tanks will carry a suitable number of oars, and other devices as requisite as well as food, medicines, signaling means, etc.

Moreover, it will be possible to arrange a pair of bilge keels in order to increase the stability of the boat.

From the foregoing specification it is apparent that the above objects are all attained by means of the improved boat according to the invention.

In fact, owing to the substantially round cross section and the fact that the boat can be hermetically closed as well as to the arrangement of the horizontal and vertical fenders and of the rolling ball corkfenders, the boat may be safely launched even if the ship is heeling over at a heavy angle. Moreover, as the hull is adapted to be hermetically closed, it is practically immaterial if it is launched in an inclined position.

Further the side doors, which are of a suitable number, will entail a more orderly embarkation than is ordinarily the case particularly in emigrant ships, avoiding the chaotic crowding over the sides of the boat, as customary in many such cases,—once clear of the ship, the boat, with doors and portholes closed will obviously resist the very strongest gale being practically turned into a buoy, affording a comfortable shelter to the occupants from cold, rain or ice.

Further it will be apparent that while I have particularly described the above preferred embodiment of what I consider my invention, many changes will be possible to the said embodiment, though remaining within the spirit of the invention or the scope of the appended claims.

Thus for instance it will be possible to make the upper part of the hull of an oval transversal section, instead of a round one, or also, as already indicated, the fore and aft ends could be of ogival or other rounded form, instead of hemispherical, etc.

Having now particularly described and ascertained the nature of my said invention and in what manner the same is to be performed, I declare that what I claim is:

1. In lifeboats, a thoroughly closed hull of substantially cylindrical shape with hemispherical fore and aft ends; a suitable number of doors on the upper sides, suitable ventilator tubes and means for hermetically closing same from the interior, suitable horizontal fenders arranged towards the periphery of the largest horizontal sectional plane; a number of vertical fenders arranged stem, and sternwards and a number of outwardly projecting stirrup members arranged below the plane of the horizontal fender and supporting each of a pivoted ball-like corkfender for ensuring the safe lowering of the lifeboats down the inclined side of a heeling ship; and suitable driving, governing, and steering means, as well as storage and other tanks and commodities as usual or prescribed in lifeboats.

2. In lifeboats, a thoroughly closed hull of substantially cylindrical shape with hemispherical fore and aft ends; a suitable number of doors on the upper sides, suitable ventilator tubes and means for hermetically closing same from the interior; suitable horizontal fenders arranged towards the periphery of the largest horizontal sectional plane; a number of vertical fenders arranged stem, and sternwards and a number of outwardly projecting stirrup members arranged below the plane of the horizontal fender and supporting each a pivoted ball-like corkfender for ensuring the safe lowering of the lifeboats down the inclined side of a heeling ship; suitable driving, governing, and steering means, raised floors along the quickwork of the boat, providing for double bottom tanks for fuel and fresh water supply, and usable as ballast; a suitably faired recess under the stern for accomodating the propeller and rudder; internal combustion engine inside the hull; a propeller shaft; a steering wheel and a water tight dome amidships with suitable portholes to allow the helmsman to inspect the surroundings.

In testimony whereof I affix my signature,
DAVID S. NEILL.
